(57) **CLAIM**

The ornamental design for a kids' electric vehicle, as shown and described.

DESCRIPTION

FIG. 1 is a top, front and right side perspective view of a kids' electric vehicle, showing my new design;

FIG. 2 is a top, rear and left side perspective view thereof;

FIG. 3 is a bottom and left perspective view thereof;

FIG. 4 is a bottom perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

Any broken lines represent boundaries of the claimed design. The areas bound in broken lines and shown in half-tone de-emphasized shading illustrates portions of the vehicle that form no part of the claimed design. Neither the broken lines themselves nor the lightened areas contained within the broken lines form any part of the claimed design.
